UNITED STATES PATENT OFFICE.

LLOYD B. SOLEMINK, OF SAN FRANCISCO, CALIFORNIA, ASSIGNOR TO A. SCHRADER'S SON, INCORPORATED, OF BROOKLYN, NEW YORK, A CORPORATION OF NEW YORK.

DEVICE TO UNSEAT TIRE VALVES.

Application filed July 18, 1921, Serial No. 485,533. Renewed February 3, 1923.

To all whom it may concern:

Be it known that I, LLOYD B. SOLEMINK, a citizen of the United States, residing at San Francisco, in the county of San Francisco and State of California, have invented certain new and useful Improvements in Devices to Unseat Tire Valves, of which the following is a specification.

This invention relates to valves of the type which are utilized in connection with pneumatic vehicle tires and the primary object of the invention is to provide an improved means for unseating the valve, in order to facilitate the deflating of the tire.

15 In the ordinary procedure of deflating an inner tube of a tire, the valve is manually held unseated which is a tiresome and tedious procedure or the whole valve is removed from the stem, which subjects the valve to breakage or displacement and the likelihood of the same becoming clogged with dirt. There is also a danger in this procedure in the cap itself becoming lost, while detached from the stem.

20 It is therefore a prime object of this invention to provide a novel cap provided with means for holding the same on the stem of a valve casing in an inverted position and a novel means formed on the cap for engaging the valve stem when in this position in order to hold the valve unseated, and thereby eliminate the inconveniences as outlined above.

25 A further object of the invention is to provide a valve cap having resilient means formed thereon for holding the same in position on the valve stem and a novel means arranged adjacent to the resilient means for engaging and depressing the valve stem.

30 A still further object of the invention is to provide an improved cap having valve deflating means formed thereon of the above character, which is durable and efficient in use, one that is simple and easy to manufacture, and one which can be placed upon the market at a reasonable cost.

35 With these and other objects in view, the invention consists in the novel construction, arrangement and formation of parts, as will be hereinafter more specifically described, claimed and illustrated in the accompanying drawings, forming a part of this specification, in which drawings:

40 Figure 1 is a fragmentary longitudinal

sectional view through an ordinary valve showing a valve cap constructed according to my invention in engagement therewith for holding the valve stem in its unseated position in order to facilitate deflating of a tire.

45 Fig. 2 is an enlarged longitudinal section through the valve cap and,

Fig. 3 is a top plan view of the valve cap. Referring to the drawings in detail, 50 wherein similar reference characters designate corresponding parts throughout the several views, the letter A indicates the novel valve cap and B an ordinary valve of the type utilized on inner tubes of vehicle tires.

55 The valve B includes the usual valve casing 5 having the valve seat 6 therein against which is adapted to fit the usual valve 7, which includes the outwardly extending 60 valve stem 8.

65 The valve cap A is constructed along the lines of the usual or approved cap and includes the body 9, which is provided with the internal threads 10 for engaging the 70 external threads 11 formed on the reduced portion 12 of the valve casing 5. The valve casing 5 is provided with threads 13, for the reception of the usual dust or guard cap, which has not been shown. The outer 75 end of the body 9 is provided with the usual reinforcing annular rib 14 and the extreme outer end of the cap is provided with an outwardly extending nipple or screw driver extension 15. The outer end of the nipple 15 is provided with a slot 16 in order to engage 80 the valve insides when it is desired to remove the same from the casing 5. The valve cap A is provided with a packing 85 gasket 16', for engaging the outer end of the reduced portion 12 of the casing 5 to seal the same against the entrance of dust 90 and leakage of air from the tire. As far as described, it can be seen that the valve cap is of the ordinary type. The outer end of the body portion 9 is provided 95 with an outwardly extending lug 17 which provides a shoulder or head 18, the purpose of which will be hereinafter more fully described. This lug 17 does not project beyond the external threads 13 formed on 100 the casing 5, so as to be out of the way of the ordinary dust and guard cap when the same is fitted on the casing. The outer end of the body 9 is also provided with an out-

wardly extending inclined resilient leg or member 20 the free terminal of which is provided with a tooth 21, which is adapted to engage in the internal threads 22 formed 5 on the inner surface of the reduced extension 12 of the casing 5, the purpose of which will be also hereinafter more fully described. -The nipple 15 formed on the outer end of the body 9 is provided with a longitudinally extending rack face 23 directly opposite to the resilient leg 20, as is clearly shown in Figures 1 to 3 of the drawings.

When it is desired to deflate the tire and unseat the valve 7 it is merely necessary to 15 remove the cap A from the reduced extension 12 of the casing 5 and invert the same. The resilient leg 20 is slid into the reduced extension 12, while the nipple 15 takes a position along side of the reduced extension 12 20 in intimate engagement therewith. The rack face 23 formed on the nipple 15 engages the external threads 11 of the reduced extension 12 while the tooth 21 engages the internal threads 22. The resiliency of the leg 20 holds the rack face 23 in engagement with the threads 11 and absolutely prevents the 25 displacement of the cap from the stem casing. The shoulder or head 18 engages the valve stem 8 and depresses the same as is apparent by referring to Figure 1 of the drawing. Thus it can be seen that when it is desired to deflate the valve it is merely necessary to place the cap in the position shown in Figure 1 which will effectively unseat the valve and permit the air to escape 30 from the tire. The tire inner tube can then be readily and conveniently rolled up by a single person without any difficulty whatsoever.

40 From the foregoing description, it can be seen that an exceptionally simple and durable device has been provided for permitting the ready deflation of an inner tube when desirable.

45 Changes in details may be made without departing from the spirit or scope of this invention, but what I claim as new is,

1. The combination with a pneumatic tire valve including a casing and a valve 50 stem, of a cap for the casing including a projection adapted to engage the outer end of the casing, resilient means formed on the cap for engaging the inner surface of the casing and for holding 55 the projection in intimate engagement with the outer surface of the casing and means carried by the cap for engaging the valve stem to hold the valve unseated.

2. The combination with a pneumatic tire valve including a casing and a valve stem, 60 of a cap for the casing including a body having a screw driver projection adapted to engage the outer end of the casing when in an inverted position, resilient means carried by the cap arranged to engage the inner surface of the casing to hold the projection in intimate contact with the outer surface thereof, and a shoulder on the cap arranged to engage the valve stem to hold the same in a depressed position when the cap is in its 65 inverted position on the valve casing.

3. The combination with a pneumatic tire valve including a casing having internal and external threads formed thereon and a valve inside therein, of a cap having an internally 75 screw threaded body, and a reduced projection, said projection having a rack face arranged to engage the external thread of the casing when the cap is in its inverted position, a resilient member carried by the 80 cap arranged to engage the inner threads of the casing for holding the rack face and the projection in engagement, and a shoulder formed on the cap arranged to depress the valve stem when the parts are in said 85 position.

4. A valve cap comprising a body, a radially extending lug formed on the body of the cap defining a valve stem engaging shoulder and a resilient member formed on 90 the cap arranged to engage the inner surface of the stem of the valve casing.

5. A valve stem cap comprising a body, and an outwardly extending projection, a radially extending lug formed on the outer 95 surface of the body defining a valve stem engaging shoulder, a resilient leg formed on the lug, a tooth formed on the outer end of the resilient leg, and a rack face formed on the projection directly opposite said resilient leg.

6. A combined valve cap and deflator, comprising a body portion and an axial projection, said parts having means adapted to engage both the interior and exterior of the 105 end of a valve casing and hold the valve therein unseated.

7. A combined valve cap and deflator, comprising a body portion having a part adapted to unseat the valve within a valve 110 casing, and spring means adapted to engage the interior of the valve casing to hold the body portion in valve unseating position thereon.

LLOYD B. SOLEMINK.
